(57) **CLAIM**

The ornamental design for a cover for a can and bottle insulator, as shown and described.

DESCRIPTION

FIG. 1 is a top perspective view of a cover for a can and bottle insulator showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof;

FIG. 8 is a right-side view thereof;

FIG. 9 is a top perspective environmental view thereof after installed on a can and bottle insulator;

FIG. 10 is a top perspective environmental view thereof after installed on a can and bottle insulator containing a can; and,

FIG. 11 is a top perspective environmental view thereof after installed on a can and bottle insulator containing a bottle. The broken line showing of the cover for a can and bottle insulator is for the purpose of illustrating the environmental structure and forms no part of the claimed design.

1 Claim, 11 Drawing Sheets
